UNITED STATES PATENT OFFICE.

DUDLEY S. SEYMOUR, OF OAK PARK, ILLINOIS, ASSIGNOR TO UNION SPECIAL MACHINE COMPANY, OF CHICAGO, ILLINOIS, A CORPORATION OF ILLINOIS.

THREAD-CUTTER FOR SEWING-MACHINES.

1,227,843.

Specification of Letters Patent. Patented May 29, 1917.

Application filed June 18, 1913. Serial No. 774,411.

To all whom it may concern:

Be it known that I, DUDLEY S. SEYMOUR, a citizen of the United States, residing at Oak Park, in the county of Cook, State of Illinois, have invented certain new and useful Improvements in Thread-Cutters for Sewing-Machines, of which the following is a description, reference being had to the accompanying drawing and to the figures 10 of reference marked thereon.

The invention relates to new and useful improvements in thread cutters for sewing machines, and more particularly to thread cutters which are used for cutting the 15 thread between stitched articles.

An object of the invention is to provide a thread cutter in the rear of the stitch forming mechanism which is under the control of the operator, and may be caused to be actuated at will by the connecting of the movable 20 blade of the cutter with a moving part of the stitch forming mechanism.

A further object of the invention is to provide a cutting mechanism of the above 25 character with devices which automatically disconnect the cutter from its actuating mechanism when released by the operator.

These and other objects will in part be 30 obvious and will in part be hereinafter more fully disclosed.

In the drawings, which show by way of illustration one embodiment of the invention,

Figure 1 is a front view of a sewing machine having my improvements applied thereto, the casing being broken away to show the rock lever for connecting the cutter to the actuating mechanism;

Fig. 2 is a detail showing in front elevation the cutting mechanism and the moving parts of the stitch forming mechanism with which the cutter is connected for actuation;

Fig. 3 is a plan view partly in section showing the cutter actuating mechanism and the controlling rock lever therefor, the cutter being disconnected from the actuating mechanism.

Fig. 4 is a similar view showing the cutter connected to the actuating mechanism

and the movement of the actuating mechanism in dotted lines to a point where the cutter is automatically released.

My invention is shown applied to a sewing machine which is especially adapted for making bags. Said machine consists of a supporting base or bed 1, on which is mounted a standard 2, having an overhanging arm 3, carrying a needle head 4, in which reciprocates a needle bar 5, carrying a needle 6. The needle bar is reciprocated by a needle actuating lever 7, which is connected to the needle bar by a link 8. The needle actuating lever is moved about its pivotal support by a link or pitman 9, which co-operates with an eccentric on the main shaft 10. As the main shaft rotates, the lower end of the pitman or link 9 will be raised and lowered and will also be moved laterally. The upper end of this link or pitman is connected to a ball stud indicated at 11 in Fig. 2. This permits the above movements in the link or pitman 9, while the needle bar actuating lever moves up and down in a vertical plane.

The material to be stitched is held on the work support 12 by a presser foot 13, which is carried by a presser bar 14. This presser foot is of a well-known character, which permits the stitching of the bags or articles which are being sewed, and the enchainment 80 of the stitching threads from one stitched article to another as they pass through the sewing machine.

Located in rear of the stitching mechanism is a thread cutter, which, as herein shown, consists of a lower fixed blade 15 and an upper movable shear blade 16. These blades are so located as to lie in a plane cutting the line of feed at right angles, and are so disposed that when the upper 90 movable shear blade is raised, as shown in Fig. 2, the articles being stitched are fed between the blades, and the enchainment threads between the stitched articles will also be carried between the shear blades.

The upper movable shear blade 16 is pivoted at 17 to a rock shaft, which is mounted in suitable bearing 18. A spring

19 encircles said rock shaft and bears against an arm 20, secured to the rock shaft, and this spring normally tends to hold the movable blade in shearing contact with the 5 fixed blade. The arm 20 projects through a slot 21 formed at the inside of the standard. A sleeve 22 is carried by the inner end of the arm and this sleeve is provided with a spring-pressed lug 23. The lug is 10 formed with a shouldered section 24, indicated in dotted lines in Fig. 4, and the spring 25 rests at one end against said shouldered section, while the other end bears against a seat formed in the sleeve 22. This 15 spring normally presses the lug 23 to the position shown in Fig. 3, so that the end 26 thereof is substantially housed in the sleeve. A stop screw 27 engages the shouldered section on the opposite face from that 20 engaged by the spring, and limits the movement of the lug through an action of the spring.

An arm 28 is clamped to the link or pitman 9 by a clamping screw 29. This arm 25 projects laterally from the link or pitman 9, and is formed with a flat horizontal face 30. When the spring-pressed lug 23 is forced forward so as to move the end 26 thereof out of the sleeve, said lug is brought 30 into the path of the movement of the arm 30. The arm 30 has an up and down and also a lateral movement. When the arm moves upward and the lug 23 is pressed forward, said arm will engage the lug and 35 will oscillate the rock shaft supporting the movable cutter, causing said movable cutter to be depressed into cutting or shearing relation with the fixed cutter 15. As the arm 30 reaches the upper end of its reciprocation, it will be carried laterally and even if the lug 23 is held pressed in its full forward position, said arm 30 will move outward on the lug to the dotted line position in Fig. 4, and this allows the lug to slip off 45 from the arm. The spring 19, above referred to, not only holds the blades in shearing relation, but said spring at one end is connected to the arm 20 while the other end is connected to the bearing 18, and the 50 spring is so wound as to normally hold the movable blade 16 in raised position. As soon, therefore, as the arm 30 moves so as to release the lug 23, the spring 19 at once raises the shearing blade. When the link or 55 pitman 9 moves up, the needle is carried upward thereby. The feed of the machine takes place when the needle is out of work, and, therefore, it is desirable that the cutting blade shall be also raised at this time 60 when the needle is up and when the feed takes place. The above construction, wherein the cutter is released from its actuating mechanism and automatically raised to its highest position, substantially while

the needle is at its extreme upper position, 65 prevents the cutter being in depressed position during the feeding action. A continued movement of the arm 30, if the lug is held pressed in, will again pick up the lug as it moves around underneath the same, 70 and a second time depress the cutter into shearing action with the fixed member.

As a means for manually controlling the cutter-actuating mechanism, I have provided a rock shaft 31, which is mounted in 75 a suitable bearing in the front plate of the standard, and said rock shaft at one end is provided with an arm 32, which depends from the rock shaft and lies in such position as to engage the lug 23 when the rock 80 shaft 31 is oscillated. A handle or finger piece 33 is also attached to the rock shaft 31, and depends therefrom so that when said finger piece is engaged and moved inwardly 85 toward the standard of the machine, the arm 32 will be swung upwardly, engaging the lug 23 and moving the inner end of the lug 26 into the path of travel of the arm 30. The front face of the arm 32 is so formed as to permit the cutter to be raised 90 while the finger piece is pressed inward.

The spring 25 forcing the lug 23 to the position shown in Fig. 3, will move the rock shaft 31 so as to move the finger piece 33 away from the standard. As long as the 95 finger piece is pressed inward, the cutter on each stroke of the needle will be coupled to the actuating mechanism and actuated, but the cutter will be released from the actuating mechanism during the penetrating 100 stroke of the needle, as above noted.

While I have described the cutting mechanism as particularly adapted for cutting the threads enchain between stitched articles, it will also be obvious that the cutting mechanism is adapted for cutting other things, such as a binding tape or the like, and said cutting mechanism may, therefore, be otherwise located relative to the stitch-forming mechanism from that herein shown 110 and described.

It is obvious that minor changes in the details of construction and the arrangement of parts may be made, without departing 115 from the spirit of the invention, as set forth in the appended claims.

Having thus described my invention, what I claim is:

1. The combination with stitch forming mechanism, of a thread cutting mechanism including a movable cutter blade located in rear of the stitch forming mechanism, and manually controlled means for causing said cutting mechanism to be actuated from a moving part of the stitch forming mechanism at the will of the operator, said manually controlled means including devices for automatically disconnecting the movable 120

125

blade from its actuating mechanism, and raising the same.

2. The combination with stitch forming mechanism, of a thread cutting mechanism including a stationary cutter blade and a movable cutter blade located in rear of the stitching mechanism, and in a plane at right angles to the line of feed, and manually controlled means for actuating the movable blade from a moving part of the stitch forming mechanism at the will of the operator, said manually controlled means including devices for automatically disconnecting the movable blade from its actuating mechanism, and raising the same when released by the operator.

3. The combination with a stitch forming mechanism including a needle, of a thread cutting mechanism including a fixed blade, a movable blade, said cutting blades being located in rear of the stitch forming mechanism and in a plane at right angles to the line of feed, and manually controlled means for actuating said movable blade from a moving part of the stitch forming mechanism at the will of the operator, said means including devices for depressing the movable blade on the upward stroke of the needle and for releasing the same.

4. The combination with a stitch forming mechanism including a needle, of a thread cutting mechanism including a fixed blade, a movable blade, said cutting blades being located in rear of the stitch forming mechanism and in a plane at right angles to the line of feed, and manually controlled means for actuating said movable blade from a moving part of the stitch forming mechanism at the will of the operator, said means including devices for depressing the blade on the upward movement of the needle, releasing the same, and raising said blade.

5. The combination with stitch forming mechanism including a needle, of a thread cutting mechanism including a movable cutter blade pivoted to swing in a plane at right angles to the line of feed and in rear of the needle, a spring for normally holding said cutting blade raised, an arm attached to said cutting blade for moving the same, an actuating device movable in unison with the needle, manually controlled means carried by the arm and movable into the path of the actuating device for depressing the cutter, said means being so disposed as to be automatically disconnected from its actuating device when the needle is substantially at the upper end of its stroke.

6. The combination with stitch forming mechanism including a needle, of a thread cutting mechanism including a movable cutter blade pivoted to swing in a plane at right angles to the line of feed and in rear of the needle, a spring for normally holding

said cutting blade raised, an arm attached to said cutting blade for moving the same, an actuating device, a lug carried by the arm, and normally held out of the path of movement of the actuating device, an arm for engaging the lug and moving the same into the path of the actuating device, and a finger piece connected to the arm for moving the lug, whereby said cutter may be connected at will to the actuating device.

7. In combination with a stitch-forming mechanism, a thread-cutting mechanism including a movable cutter blade located in rear of the stitch-forming mechanism, manually-controlled means for causing said cutting mechanism to be actuated from a moving part of said stitch-forming mechanism and for releasing the same without stopping the stitching mechanism, said cutting mechanism being normally positioned with its cutting blade raised for its next cutting action.

8. In combination with a stitch-forming mechanism, a thread-cutting mechanism including a movable cutter blade located in rear of the stitch-forming mechanism, manually-controlled means for causing said cutting mechanism to be actuated from a moving part of the stitch-forming mechanism and for releasing the same without stopping the stitching mechanism, said cutting mechanism being normally positioned with its cutting blade raised for its next cutting action, and automatic means for restoring said blade to its normal position after each cutting action.

9. The combination of a work support, a standard, an overhanging arm carried thereby, a needle mounted in said overhanging arm, a thread-cutting mechanism including a cutting blade located in rear of the needle, means for actuating said cutting blade, and manually-controlled devices located underneath the overhanging arm for controlling the action of said cutting blade.

10. In combination with stitch-forming mechanism including a needle, a feeding device operating to feed the fabric being sewed forward at a period of time when said needle is above the fabric, a thread-cutting mechanism, and means to operate it, whereby its cutting action will take place while said needle is making its upward stroke and before the feeding device starts to move the fabric forward.

11. In combination with stitch-forming mechanism including a needle, a feeding device operating to feed the fabric being sewed, a thread-cutting mechanism including a cutting blade, and means to operate it, whereby its cutting action takes place while said needle is above the material being stitched and while said material is firmly held between the feed dog and the presser

foot, and means to hold said blade in a raised position during the time the fabric is being fed forward by the feeding device.

12. The combination of a stitch-forming mechanism including a member having a part thereof moving in a curved path, a thread-cutting device including a movable cutter, manually-controlled means for causing said cutting device to be actuated from 10 said moving part of the stitch-forming mechanism, the manually controlled means

for the cutter including a member moving in a plane substantially at right angles to the plane of the curved path of movement of the part of the stitch-forming mechanism. 15

In testimony whereof, I affix my signature in the presence of two witnesses.
